UNITED STATES PATENT OFFICE.

CORA McCONNELL, OF MOUNT AIRY, GEORGIA

HANGING WARDROBE.

1,071,624.

Specification of Letters Patent. Patented Aug. 26, 1913.

Application filed February 10, 1913. Serial No. 747,391.

To all whom it may concern:

Be it known that I, CORA McCONNELL, a citizen of the United States, and a resident of Mount Airy, county of Habersham, State of Georgia, have invented certain new and useful Improvements in Hanging Wardrobes, of which the following is a full and clear specification, reference being had to the accompanying drawings, in which—

10 Figure 1 is a perspective view of my rack unfolded and suspended in position for use; and Fig. 2 is a vertical sectional view on the line 2—2 of Fig. 1.

The object of this invention is to provide a light, strong and durable rack for wearing apparel, means being provided whereby the rack may be readily erected in any suitable place and also whereby the rack may be folded into a compact body for ease of transportation and storage, as more fully herein-after set forth.

Referring to the drawings by reference characters, *a* designates two series of parallel bars, the bars of each series being rigidly connected together by the cross bars *b* and the bars of one series being connected to the alining bars of the other series by hinges at *c*, suitable stops or abutments *d* being provided at points above the pivots of the hinges to form a rule joint, thus limiting the upward swing of the bars. In front a supplemental pair of bars *a'* are provided similar in size and length to the bars *a* and being pivoted together in the same manner at their adjoining ends. The bars *a'* are connected to the two frames composed of the bars *a* and *b* by means of bars *e* which are rigidly connected at their front ends to the respective bars *a'* and rest slidably upon the tops of the frames composed of the bars *a* and *b*. These bars *e* are slidably connected to the cross bars *b* by clips *f*.

To each of the bars *a* is slidably connected a bar *g*, this connection being by means of clips *k* and *l*, the former being attached to the bar *g* and the latter to the extremity of the bar *a*. The outer ends of each series of bars *g* are rigidly connected by an end bar *j*, and slidably connected to each bar *j* by a clip *k* is a supplemental end bar *j'* which lies parallel with the bars *a* and closely against the bars *j*. The outer ends of the bars *j'* are connected to the bars *j* which lie against the respective supplemental bars *a'* and are slidably connected thereto by means of clips *l* and *m*, the clip *m* being attached to the bar

j' and the clip *l* being attached to the extreme end of bar *a'*.

The frame constructed as above is adapted to be suspended by a series of brackets each consisting of a vertical bar *n* and an oblique bar *o* rigidly attached at its upper end to the bar *n* and extending downwardly and forwardly therefrom. The lower end of each bar *n* is pivotally attached to the rear bars of the frame while the lower extremity of the inclined bars are pivotally attached to certain of the frame bars at the front part of the frame. The two middle ones of the bars *n* are attached to the rearmost bars *a*, and the two outer bars *n* are attached to the respective bars *g* at the rear of the frame. The two middle bars *o* are attached to the front ones of the bars *a* while the two outer bars *o* are attached to the outer ones of the bars *g*.

At intervals along the various bars are attached suitable depending hooks *p*, which may be permanently or detachably connected to the bars and may be formed as shown of twisted wire or otherwise. Some of the hooks are illustrated as turned forward while others are illustrated as turned to one side, but this arrangement may be varied without departing from my invention.

The upper ends of the bars *n* are provided with holes *q* to permit the frame to be supported upon suitable nails driven into a wall. When thus supported the bars *n* and the rearmost bars of the frame will rest against the wall and all the bars will be supported in a horizontal position, approximately in the same horizontal plane.

It will be observed that the construction is such that the frame may be shortened or lengthened by pushing in or pulling out the end frames consisting of the bars *g*, *j*, *j'* and *j''*; it will be observed further that the frame may be widened or narrowed by pulling out or pushing in the front supplemental frame consisting of the bars *a'* and the connected bars. It will be observed also that these supplemental sliding frames together with the pivoting of the parts together will enable the rack to be folded up into a compact form when it is taken down. It will thus be observed that I provide a strong, light, foldable frame which may be readily erected and which will have a large and adjustable capacity.

I wish it understood that I may provide

for inclosing my folding rack in a suitable housing preferably of fabric, for the purpose of excluding dust and that this housing may be detachably connected to the 5 rack. I may have a suitable piece of fabric to hang or place over the top of the rack and also suitable pendant fabrics which may be hung upon the end bars and also the front bar in any suitable manner, prefer- 10 ably by button holes in the fabric which shall engage over suitable hooks on said bars. For this purpose I may use the same hook as I have illustrated for the garment hangers or I may use other forms of hooks. 15 It will be understood that the garment hanger hooks may be arranged on any or all of the horizontal bars of the frame, including the back bars *a* and *g*, it being my intention to apply the hooks to any of the 20 bars wherever needed either for hanging garments or for supporting a fabric curtain around the edges of the frame.

Having thus described my invention, what I claim as new, and desire to secure 25 by Letters Patent, is—

1. A rack of the class set forth, consisting of a main frame, a supplemental frame at each end slidable inwardly and outwardly, a supplemental front frame slidable in-

wardly and outwardly, each of said frames 30 consisting of horizontal bars and the sliding connections being obtained by overlapping the bars, the front frame having sliding connection to the main frame and also to the end frames, a plurality of garment supporting hooks carried by the bars of each 35 of said frames, and suspending devices connected both to the main frame and each of the end frames.

2. In combination, a main frame consisting of two series of bars hinged together, two end frames slidably connected to the outer extremities of the bars of the main frame, a front frame consisting of horizontal bars hinged together and rearwardly 40 extending bars slidably connected to the end frame, a plurality of garment supporting hooks depending from the bars of each 45 of said frames, and means for suspending said frames as a whole, said means being pivotally connected to the frame.

In testimony whereof I hereunto affix my signature in the presence of two witnesses.

CORA McCONNELL.
